UNITED STATES PATENT OFFICE

134,333

DESIGN FOR AN EVAPORATOR

George T. Jacocks, New Rochelle, and Robert E.
Giauque, New York, N. Y.

Application March 4, 1942, Serial No. 106,080

Term of patent 14 years

To all whom it may concern:

Be it known that we, George T. Jacocks, a citizen of the United States and a resident of the city of New Rochelle, county of Westchester, and State of New York; and Robert E. Giauque, a citizen of the United States and a resident of the city of New York, county of Bronx, and State of New York, have invented a new, original, and ornamental Design for an Evaporator, of which the following is a specification, reference being had to the accompanying drawing, forming part thereof.

Fig. 1 is a perspective view of one side and one end of an evaporator showing our new design; and

Fig. 2 is a perspective view of the other side and other end thereof.

We claim:

The ornamental design for an evaporator, as shown.

GEORGE T. JACOCKS.
ROBERT E. GIAUQUE,
